PSEUDOCUMENE RECOVERY

Francis T. Wadsworth, Dickinson, Tex., assignor to The American Oil Company, Texas City, Tex., a corporation of Texas

No Drawing. Application December 27, 1957
Serial No. 705,496

4 Claims. (Cl. 260—674)

This invention relates to the recovery of pseudocumene from hydrocarbon fractions, and particularly concerns a process whereby pseudocumene can be produced in high concentration.

Pseudocumene is a desirable intermediate in the chemical industry for conversion to alcohols, carboxylic acids, and for a number of other purposes. The plastics industry is appreciating the merits of tri-carboxylic aromatic acids to a greater extent than heretofore, and a necessity for producing high purity pseudocumene has arisen. The synthesis of pseudocumene (1,2,4-trimethylbenzene) is too costly to be practical. Petroleum refiners have quantities of hydrocarbon fractions containing pseudocumene, but these fractions contain large amounts of other trimethylbenzenes, ethyltoluenes, butylbenzenes, propyltoluenes, ethylxylenes, and propylbenzenes. These contaminating aromatics are present as a mixture of all of their isomers. Because of the closeness of the boiling points of other aromatic hydrocarbons, it is not possible to separate pseudocumene fraction containing more than 70-80% pseudocumene by fractionation of petroleum naphthas. A method for producing pseudocumene in higher concentration is desired.

An object of the present invention is to provide a process for producing a hydrocarbon fraction containing a high concentration of pseudocumene from an initial hydrocarbon fraction containing a lower concentration of pseudocumene. Another object is to provide a process by which pseudocumene is recovered from reformed naphtha fractions. A further object is to provide a process by which pseudocumene in a purity of 95% and higher is produced. These and other objects will be apparent from the detailed description of the invention.

In accordance with the present invention a pseudocumene-rich fraction of hydrocarbons, substantially all of which boil within the range of 164° to 170° C., is subjected to an alkylation step in which an alkylation agent having a tertiary carbon atom, e.g. tertiary olefin such as diisobutylene, is used. A petroleum naphtha which has been catalytically reformed to convert naphthenes to aromatics may be fractionated to produce the pseudocumene-rich charge stock to this invention. Reformed naphtha charge stock to the invention may be treated by processes such as solvent extraction to remove essentially all of the paraffinic hydrocarbons prior to using the defined boiling range charge stock in the alkylation step. An alkylation catalyst (e.g. BF_3 monohydrate is highly effective in this process), is used. The products from the alkylation step are processed to separate the alkylation catalyst from the mixture of alkylated and non-alkylated hydrocarbons. The hydrocarbons are then fractionated to separate a fraction boiling approximately within the range of 164° to 170° C. from a higher boiling hydrocarbon fraction. The 164° to 170° C. fraction contains a higher concentration of pseudocumene than does the initial charge stock to the alkylation step. Ninety-five percent purity pseudocumene can

be produced when starting with a reformed naphtha fraction essentially free of non-aromatic hydrocarbons.

While others have heretofore employed the technique of alkylation a mixture of hydrocarbons selectively so that only certain C_8 aromatic isomers in the mixture are alkylated and thereafter separating alkylated from non-alkylated aromatic hydrocarbons, there has been no suggestion that pseudocumene could be recovered by such a technique. Also, the use of this technique in earlier processes did not produce one aromatic isomer in the high purity of 95%+ which is needed in subsequent chemical processing steps. The present invention is capable of producing 95%+ purity pseudocumene provided the charge stock is carefully fractionated and is essentially free of non-aromatic hydrocarbons, e.g. paraffins and olefins.

The charge stock to this invention can be a petroleum naphtha which has been reformed, preferably to an octane number of at least 100 F-1, and thereafter fractionated to recover a pseudocumene-rich fraction, substantially all of which boils within the range of 164° to 170° C. Prior to recovering the 164°-170° C. fraction from reformed naphtha, the reformed naphtha may be freed of paraffins and olefins by solvent extraction or extractive distillation or the like. If desired, the separation of non-aromatic hydrocarbons from the aromatic hydrocarbons can be made upon the 164°-170° C. fraction. By using naphtha which has been reformed to an octane number of at least 100 F-1, the solvent extraction step may be eliminated since only a very small percentage of non-aromatic hydrocarbons will be present in the 164°-170° C. boiling range fraction of the reformed naphtha. The pseudocumene-rich fraction from such a high octane reformed naphtha is a particularly advantageous charge stock to this invention. The 164°-170° C. pseudocumene-rich fraction which is essentially free of non-aromatic hydrocarbons will ordinarily have a pseudocumene content of about 70-80% by weight. It may contain from 1 to 5% by weight of mesitylene, depending upon the preciseness of fractionation. The other aromatic hydrocarbons consist of butylbenzene, ethyltoluenes, sometimes propylbenzenes, methylpropylbenzenes, and dimethylethylbenzenes, in their various isomeric forms.

45 The alkylation agent is one which has a tertiary carbon atom. It may be a tertiary olefin such as isobutylene, diisobutylene, triisobutylene, or the like; a poly-tertiary-alkylbenzene such as a di-tertiarybutylbenzene; a tertiary alcohol; or a tertiary-alkyl halide such as tertiary-butyl chloride, etc. Tertiary olefins are particularly useful for this purpose. The process can be made quite efficient by recycling the di-tertiary-alkyl aromatics which are produced during the alkylation step as a source of the tertiary alkylation agent.

55 The alkylation reaction may be carried out at a temperature between 0° C. to 100° C., although somewhat lower or higher temperatures may be used depending upon the particular alkylation catalyst employed. Various acidic catalysts such as have heretofore been used in aromatic alkylation may be employed. These include sulfuric acid, phosphoric acid, hydrofluoric acid, Friedel-Crafts catalyst such as aluminum chloride, boron fluoride, and the like. A boron trifluoride monohydrate catalyst, which consists of approximately (not necessarily precisely) equal mols of BF_3 and water, is a very effective catalyst for use in the alkylation step. The alkylation agent is contacted with the 164°-170° C. pseudocumene-rich fraction in the amount of at least one mole (usually 2 to 10 mols) per mol of the aromatic hydrocarbons (other than pseudocumene) which are present in the 164°-170° C. fraction. The reactants and catalyst are contacted, suitably in the liquid phase,

using reaction times of from 5 minutes to 2 hours or longer.

After completion of the reaction, the catalyst is separated from the hydrocarbons. The hydrocarbons are then fractionated to recover a 164-170° C. pseudocumene fraction which has a higher concentration of pseudocumene than the initial charge stock. If non-aromatic hydrocarbons were present in the 164-170° C. pseudocumene fraction which was alkylated, such hydrocarbons may be removed at this point, if desired, by solvent extraction, extractive distillation or similar techniques. The portion of the hydrocarbons from the alkylation step which boils above 170° C. consists of alkylated aromatic hydrocarbons. If a high ratio of alkylating agent to non-pseudocumene aromatic hydrocarbons is employed during the alkylation step, a considerable quantity of di-alkylation products may be formed. These di-alkylated aromatic hydrocarbons can be recovered and used as the source of the alkylating agent during subsequent alkylations, since one of the tertiary-alkyl substituents attached to the aromatic ring will readily detach and alkylate the non-pseudocumene aromatic hydrocarbons in the charge mixture.

The following experiment illustrates the invention. A petroleum naphtha, which had been catalytically reformed to a high octane number in the presence of hydrogen while using a platinum-alumina catalyst, was obtained. The reformed naphtha was subjected to highly efficient fractionation and a fraction boiling over the range of 164-169° C. was collected. Due to the very high octane number of the reformed naphtha, this 164-169° C. fraction contained only about 5% of non-aromatic hydrocarbons which were principally paraffins. Four hundred and eighty grams of this 164-169° C. reformate fraction, which contained .95 mols of aromatic hydrocarbons other than pseudocumene, were agitated with 2 mols of diisobutylene in the presence of 150 grams of BF_3 mono-hydrate at 25° C. for about 30 minutes. Following the alkylation reaction, the aqueous catalyst phase was separated and the hydrocarbon layer was water-washed and then dried. The dried hydrocarbon layer was then distilled using a ten-tray Oldershaw column at 10:1 reflux and a fraction boiling over the range of 164-169° C. was collected. A portion of the initial pseudocumene-rich charge stock was also redistilled under these identical conditions. The analysis of the 164-169° C. fraction which had been recovered from the products of alkylation, and the analysis of the 164-169° C. fraction which had not been subjected to alkylation are presented in Table I. These analyses are 50 presented on a paraffin-free basis.

TABLE I

Composition of 164-169° C. fraction, wt. percent

	Pseudo-cumene	Mesitylene	Other Aromatics
	Percent	Percent	Percent
Recovered from Products of Alkylation	95.3	3.5	1.2
Charge to Alkylation	77.5	3.7	18.8

It is evident from the above data that the present invention provides a method for recovering pseudocumene in high purity from hydrocarbon fractions such as reformed petroleum naphthas.

Thus having described the invention, what is claimed is:

1. A process which comprises contacting in the liquid phase a pseudocumene-rich hydrocarbon fraction, which is essentially free of non-aromatic hydrocarbons and boils within the range of 164° to 170° C., with diisobutylene in the amount of at least one mol per mol of the aromatic hydrocarbons other than pseudocumene which are present in the charge pseudocumene-rich fraction and with a BF_3 mono-hydrate alkylation catalyst at a temperature between about 0° and 100° C. and thereby producing a mixture of alkylated and non-alkylated aromatic hydrocarbons, separating the catalyst from the mixture of alkylated and non-alkylated hydrocarbons, and fractionally distilling the mixture of alkylated and non-alkylated hydrocarbons to separate a pseudocumene fraction which boils within the range of 164° to 170° C. and which contains pseudocumene in a concentration of at least 95% from a higher boiling alkylated aromatic hydrocarbon fraction.

2. A process which comprises contacting a pseudocumene-rich fraction of hydrocarbons, substantially all of which boils within the range of 164° to 170° C., with an alkylation catalyst and an alkylating agent having a tertiary carbon atom under alkylation conditions whereby a portion of the hydrocarbons contained in the pseudocumene-rich fraction is alkylated, and distilling products from the alkylation step to separate a non-alkylated fraction enriched in pseudocumene and boiling approximately within the range of 164° to 170° C. from a higher boiling alkylated hydrocarbon fraction.

3. The process of claim 2 wherein the alkylating agent is isobutylene.

4. A process which comprises reforming a petroleum naphtha to an octane number of at least 100 F-1 clear, fractionating the reform naphtha to recover a pseudocumene-rich fraction substantially all of which boils within the range of 164° to 170° C., contacting said pseudocumene-rich fraction with an alkylation catalyst and an alkylating agent having a tertiary carbon atom under alkylation conditions whereby a portion of the hydrocarbons contained in the pseudocumene-rich fraction is alkylated, and distilling products from the alkylation step to separate a non-alkylated fraction enriched in pseudocumene and boiling approximately within the range of 164° to 170° C. from a higher boiling alkylated fraction.
